TUBE CLEANING DEVICE

Kenneth MacKenzie Urquhart, New York, N. Y.,
assignor to Socony-Vacuum Oil Company, Incorporated,
New York, N. Y., a corporation of
New York

Application November 4, 1941, Serial No. 417,768

2 Claims. (Cl. 15—104.055)

This invention relates to a device for cleaning tubes and is concerned particularly with a device for scavenging and cleaning tubes arranged in parallel by admitting a stream of high pressure cleaning fluid to each of said tubes.

The invention, in one specific embodiment is admirably adapted for cleaning of perforated tubes such as are used in chambers for catalytic cracking of heavy mineral oil fractions to obtain products boiling within the range of gasoline. As shown in Patent No. 2,231,493, issued February 11, 1941, to Leland W. T. Cummings, a chamber of this type is normally equipped with a plurality of inlet conduits and a plurality of outlet conduits extending into a body of granular catalytic material, each of the conduits being in the form of a pipe, closed at the end embedded in the catalyst and having orifices at spaced points along its length. The outlet or collector tubes are particularly subject to fouling of the orifices because the flow therethrough is from a region in which carbonaceous matter is formed from the hydrocarbon vapors under treatment. It is therefore necessary to clean the collector tubes from time to time by removing the top of the catalyst case to open the vapor space above the tube sheet from which the collector tubes extend into the catalyst bed.

The apparatus of this invention is designed to clean the tubes of a case opened in the above manner rapidly and efficiently. Means are provided whereby air, steam or the like is admitted to the ends of the collector tubes while said means are maintained in operative blowing relationship with said tubes by means of the pressure of the cleaning fluid. The invention also contemplates the provision of an apparatus whereby the operative blowing relationship is established by reason of said pressure after adjustment of the apparatus to the desired position.

The nature of the invention will be more fully understood from the description hereinafter, when considered in connection with the annexed drawing, wherein

Figure 1 is a top plan view of a preferred form of the invention;

Figure 2 is a sectional view on line 2—2 of Figure 1;

Figure 3 is partial rear elevation of the same device; and

Figure 4 is a detailed longitudinal section of the nozzle used in the apparatus.

The apparatus in its preferred form comprises three nozzles 10 for applying a flow of cleansing steam to the collector tubes, the nozzles being

arranged relative to each other according to the arrangement of tubes within the catalyst case. The nozzles are carried on pipes 11 extending downwardly from a casing 12 which defines a steam chest 13 in cooperation with a cover plate 14, the casing and cover plate being secured together, as by bolts 15 and having a gasket 16, preferably of a metal such as aluminum, therebetween. Depending from the casing 12 and integral therewith are a plurality of cylinders 17 in each of which is mounted a hollow piston 18 having a shoulder 19 to engage the bottom of the steam chest and thereby limit outward movement of the piston. The piston 18 is further designed with a shoulder 20 and packing material 21 is maintained below said shoulder 20 between cylinder 17 and tube 18 under pressure applied through packing bushing 22 by a packing nut 23 threaded on the lower portion of the piston 18.

A pipe 11 is threaded into the lower end of each piston 18 and carries a nozzle 10 at its lower end. The nozzle, as shown in Figure 4 is formed with a depending skirt 24 surrounding a nipple 25 to define an annular space for a gasket 26 of rubber or the like. The inner surface of the skirt 24 and the outer surface of the nipple 25 are tapered to guide the end of the collector tube into engagement with the gasket 26 when a cleaning operation is to be undertaken.

Attached to the top surface of the plate 14 are two guide members 27 formed to fit on an I-beam whereby the beam may be utilized as an overhead track and backing element for the apparatus. A pair of handles 28 each welded to one of the pipes 11 are used for manual centering of the device over a set of three collector tubes to be cleaned.

Means are also provided for manually retracting the pipes 11 and nozzles 10 carried thereby after a blowing operation, which means comprises a pair of levers 29 pivotally connected to a sleeve-like retractor plate 30 having as their fulcrums a pivotal connection with links 31, the latter being connected by pivot joints 32 to the casing 12. It will be seen that an upward force exerted on the outer end of levers 29 will act through a link 33 on the lower surface of retractor plate 30 to force piston 18 upward and thus withdraw nozzles 10 from engagement with the ends of collector tubes. In normal operation, the device may be centered sufficiently well by manipulation through use of the levers 29 only. As a rule, the handles 28 need only be used when the tube pattern is varied slightly or a single tube has the end thereof out of normal position.

In operation of the device, an I-beam is tem-

porarily installed above an opened catalyst case along a selected line of pairs of collector tube ends extending above the tube sheet. The cleaning device is then slidably mounted on the I-beam by engagement of guide members 27 with the edges of the beam and the device centered over a group of three collector tube ends and lowered to engage therewith by manual adjustment through use of handles 28. Steam is then admitted to steam chest 13 under a pressure of 250 to 300 pounds per square inch through an inlet port 34. Steam will, of course, pass through the pipes 11 and the nozzles 10 to the collector tubes, a portion thereof leaking out between the nozzles and collector tubes at the beginning of the blow. However, the pressure will exert a force on the pistons 18, by reason of the fact that the diameter thereof is restricted in the direction of steam flow, thus forcing the nozzles 10 into tight engagement with the ends of the collector tubes. This results in the full force of the steam pressure being exerted in blowing out the collector tubes to clean the orifices thereof by removal of carbonaceous material and other matter tending to reduce the size thereof.

The gaskets 26 are formed of rubber or the like, preferably a synthetic rubber having a high power of resistance to the deteriorating effects of steam; since a leak, once developed, will rapidly enlarge under the erosive action of steam passing therethrough at high velocity, ending in complete failure of the gasket. It is possible to use compressed air and thus avoid steam action on the gasket, but this requires a very large compressor if serious pressure drops during the blowing are to be avoided. When using air with the present apparatus, a large storage tank has been used, thus permitting the pressure to build up to a proper level between blowing of two sets of three tubes.

Upon reference to Figure 2 it will be noted that the interior cross sectional area of the conduit defined by piston 18 is progressively reduced from a maximum at the outlet to chamber 13 to a minimum at the point of connection of pipe 11. Thus, the working surface of each piston 18 is the same as if the opening into chamber 13 were of the same diameter as the opening into pipe 11. The pressure effect, however, is quite different in that, under flow conditions, velocity is progressively increased in each piston 18 as the cross sectional area of the conduit defined thereby is reduced. This, of course, brings about a stage reduction in pressure. Thus, the total pressure exerted on each piston 18, when steam is flowing therethrough, is not as great as if all of the working surfaces lay in the same plane. The result of this is that there is ample pressure to maintain a seal at gasket 26 and yet the gasket is not damaged by excessive pressure while, of course, the desired increase in flow velocity is attainable. On the other hand, if the tube to be cleaned is wholly clogged and the steam becomes static, the force exerted by the piston on the gasket 26 can rise to a value equal to that attainable with the same size piston having all working surfaces in the same plane.

The device described above is well suited to use in a combined cleaning and testing apparatus. If a pressure gauge and orifice meter, or other

suitable indicating means be installed in the pressure line, changes in pressure and rate of flow are very good indications of cleanliness of tube orifices. This avoids a separate testing step and the possibility the cleaning device may have to be replaced in blowing position one or more times to complete the cleaning operation.

I claim:

1. Apparatus for cleaning tubes comprising, means defining a chamber for a fluid under pressure, means for introducing fluid under pressure into said chamber, means defining a cylinder depending from said chamber and in communication therewith, a hollow piston slidable in said cylinder, means for limiting the outward stroke of said piston, a pipe attached to and depending from one end of said piston, a nozzle on the end of said pipe remote from said piston, said nozzle terminating in a depending skirt about and spaced from a nipple and defining therewith an annular cavity and a resilient gasket in the bottom of said cavity, said hollow piston defining a passageway progressively decreasing in cross sectional area between said chamber and said pipe, the greatest cross sectional area of the passageway being less than the cross sectional area of the chamber and the least cross sectional area of the passageway being about equal to the cross sectional area of the pipe, whereby the zone of greatest pressure will cause extension of the piston which, acting through the pipe, will seal the skirted end of the latter against a tube to be cleaned while the skirted end of said pipe will permit the use of a nipple of slight thickness so that variations in flow velocity between the pipe and the tube to be cleaned may be minimized and yet flow velocity may be maintained at a high value without leakage at the joint between the pipe and the tube to be cleaned.
2. Apparatus for cleaning tubes comprising, a plurality of cylinders, a piston in each cylinder, means for supplying a fluid under pressure to each cylinder to cause extension of the piston therein, each piston having a fluid passageway therethrough, a pipe attached to and depending from one end of each piston, said pipe constituting a continuation of the passageway through the piston, means defining a seat for a gasket at the end of each pipe remote from its point of attachment to the respective piston, a gasket in said seat adapted to be pressed against the end of a tube when the piston and pipe are extended, means defining an engaging surface on each piston and pipe unit, said means lying the same distance below the top of each piston, a slideable sleeve common to all the pipes and adapted to engage the engaging surface to retract the pistons, whereby, when the pistons are extended to different degrees due to variations in the planes in which the ends of the pipes lie, they may be manually retracted to the same point by operation of the means for moving the sleeve, which latter first engages the engaging surface of the most extended piston and subsequently those of the less extended pistons until all of the engaging surfaces are engaged, whereupon all of the pistons may be retracted for any desired distance to lie in a single plane.

KENNETH MACKENZIE URQUHART.
